UNITED STATES PATENT OFFICE.

ALBERT CHRISTEN, OF HASTINGS-ON-HUDSON, NEW YORK, ASSIGNOR TO CONSOLIDATED SHIPBUILDING CORPORATION, OF NEW YORK, N. Y., A CORPORATION OF NEW YORK.

TOILET SYSTEM FOR VESSELS.

Application filed January 5, 1924. Serial No. 684,618.

To all whom it may concern:

Be it known that I, ALBERT CHRISTEN, a citizen of the United States, and a resident of Hastings-on-Hudson, in the county of 5 Westchester and State of New York, have invented a new and Improved Toilet System for Vessels, of which the following is a full, clear, and exact description.

This invention relates to improvements in 10 toilet systems, and has particular reference to a system to be used on vessels.

An object of the invention is to provide 15 an improved system of simple, practical and efficient construction, in which water is pumped to and from the bowl in such a manner as to effectively flush the same and prevent clogging of the system.

The above and other objects will appear 20 more clearly from the following detailed description when taken in connection with the accompanying drawings, which illustrate a preferred embodiment of the inventive idea.

In the drawings—

25 Figure 1 is a fragmentary sectional view of a vessel showing the system in side elevation.

Figure 2 is a sectional view through the 30 pump construction on substantially the line 2—2 of Figure 3;

Figure 3 is an enlarged view, partly in 35 side elevation and partly in longitudinal section, of the pump construction and the operating means therefor;

Figure 4 is a transverse section on the 40 line 4—4 of Figure 3; and

Figure 5 is a similar view on the line 45 5—5 of Figure 3.

The invention is shown in connection 50 with a vessel 6 which may be of any construction and in which is suitably supported at a convenient place the usual bowl 7 to which is connected at its upper end an inlet 8 and at its lower end an outlet pipe 9.

55 The pump construction utilized in connection with the present invention consists of a base 10 suitably supported at a convenient place and carrying a casting which includes a force pump cylinder 11 and a discharge pump cylinder 12 arranged contiguous to each other and separated by a partition 13 which forms one end of the cylinder 11 and a wall of the cylinder 12.

60 The opposite end of the cylinder 11 is closed by a removable plate 14 while the end

of the cylinder 12 opposite the partition 13 is closed by the plate 15 having a screw threaded extension 16 to which the lower end of the outlet pipe 9 is connected. The periphery of the cylinder 12 is also provided with an externally threaded extension 17 to which is connected one end of a waste pipe 18, the other end of which is extended through the hull of the vessel 6.

65 At one end of the base 10 the same is provided with a bracket 19 to which is secured an operating element, preferably in the form of a high power electric motor 20 connected in circuit with the source of current 21, which circuit further includes

70 a switch 22 of any desired type located adjacent the bowl 7 and which, when operated, closes the circuit for the motor 20 to operate the same. The shaft 23 of the motor 20 is joined to one section of a shaft

75 24 by a coupling 25 to rotate the shaft 24 when the motor is driven. Said section of the shaft 24 extends through the plate 14 and supports upon its inner end in eccentric relation to the peripheral wall of the

80 cylinder 11 a rotor 25. This rotor is provided with an opening or slot 26 extending diametrically therethrough and in which is disposed a pair of radially movable

85 blades 27, the outer edges of which are constantly maintained in engagement with the wall of the cylinder 11 by the centrifugal force imparted to the rotor 25 by the shaft 24. At diametrically opposite

90 points the cylinder 11 is provided with internally threaded inlet and outlet openings 28 and 29 to which are connected, respectively, adjacent ends of a supply pipe 30 and the inlet pipe 8. The opposite end of the supply pipe 30 is extended through

95 the bottom of the vessel and the entrance of water into said pipe is controlled by a sea valve 31 of any desired construction.

100 The other section 32 of the shaft 24 is mounted for rotation in the partition 13 and one end of said section is utilized to form a bearing for the adjacent end of the rotor 25. The opposite end of said section 32 extends into the cylinder and supports

105 thereon a rotor 33 through which is extended radially on opposite sides of the same a blade 34 the ends of which engage the periphery of the cylinder 12.

110 In operation when the switch 22 is closed to start the electric motor 20 rotation is

imparted to the shaft 24 to operate both the rotors 25 and 33 and their respective blades. In the operation of the rotor 25, which forms a part of the force pump, 5 water is drawn through the supply pipe 30 through the inlet 28 of said pump into the cylinder 11 and from thence through the outlet 29 and inlet pipe 8 to the bowl 7. This pumping of the water 10 aids in priming the discharge pump including the rotor 33 and as the latter is driven by the shaft 24 the blade 34 will operate to discharge from the pipe 9 into the waste pipe 18.

15 What is claimed is:

A toilet system for vessels including in combination a bowl, inlet and outlet pipes

connected thereto, a pump cylinder connected to said inlet pipe and to a source of water supply, a second pump cylinder 20 connected directly to said outlet pipe, a waste pipe leading from the upper end of said second pump cylinder to a point exterior of the vessel and disposed in a plane above said second named pump, a shaft extending through both of said cylinders, rotors on said shaft, one disposed in each of said cylinders, each of said rotors being of such construction as to contact with the side walls of said cylinder during the entire revolution thereof, means for driving said shaft, and manually actuated means for operating said driving means.

ALBERT CHRISTEN,
